United States Patent Office

Des. 204,962
Patented May 31, 1966

204,962

COMBINED PACKAGING TRAY AND COVER THEREFOR

Dennis J. Kossnar, West Chicago, Ill., assignor to Container Corporation of America, Chicago, Ill., a corporation of Delaware

Filed Feb. 17, 1965, Ser. No. 83,848

Term of patent 14 years

(Cl. D58—13)

Fig. 1

I claim:

The ornamental design for a combined packaging tray and cover therefor, as shown.
